UNITED STATES PATENT OFFICE

EMIL R. FRANK, OF SIOUX CITY, IOWA, ASSIGNOR OF ONE-THIRD TO WESLEY D. GAMEL, OF SIOUX CITY, IOWA

MECHANISM FOR AUTOMATICALLY OPENING AND CLOSING GARAGE DOORS

Application filed January 25, 1928. Serial No. 249,319.

This invention relates to mechanism adapted to be used in conjunction with a garage building and operated by the automobile as it enters and leaves the garage for the purpose 5 of opening and closing the doors thereof, and it consists in the novel features hereinafter described and claimed.

An object of the invention is to provide mechanism of the character stated which is 10 of simple and durable construction and which may be readily installed in a garage building, the parts thereof being so arranged and connected that when an automobile enters the garage the wheels thereof ride upon pivoted 15 ramp plates which are rocked and being operatively connected with the doors of the garage close the same, the pivoted ramps and connections with the door being such that when the automobile starts to leave the 20 garage the said ramp plates are rocked in a reverse direction whereby the doors of the garage are automatically opened so that the machine may pass out of the building. While the garage building is vacant or empty, the 25 doors may be left in an open position so that the machine may readily enter the building without requiring the driver or operator to alight from the automobile for opening the doors.

30 In the accompanying drawings:

Figure 1 is a vertical sectional view of a garage building showing the doors in open position and with the door controlling means applied,

35 Figure 2 is a horizontal sectional view of the garage building and the door controlling means cut on the line 2—2 of Figure 1,

Figure 3 is a fragmentary sectional view 40 cut on the line 3—3 of Figure 1 and showing the door at open position, and

Figure 4 is a similar view showing the door at a closed position.

As illustrated in the accompanying drawings, the garage building 1 to which the device is applied may be of usual form or design, provided in its front wall 2 with a door opening 3 having doors 4 hinged at the opposite sides thereof. The garage building is provided with a floor 5, at the rear end of which 50 are recesses 6—6 spaced apart to correspond

with the tread of an automobile, and within these recesses are pivoted curved ramp plates 7 each pivoted intermediate its end to have a rocking motion, with that part of the plate immediately above the pivot on a plane, approximately, with the plane of the upper surface of the floor and the latter recessed, as shown in Fig. 1 to form a stop for limiting the rocking movement of the ramp plate in one direction. It will be noted that the ramp plates are each reinforced by a rib formed integrally at the inner side thereof, and that the rear end of said rib terminates in an eye 7^a for convenience in attaching the connections between said ramp plates and the devices hereinafter described operating directly on the doors for opening and closing the same. Bell crank levers 8 are pivoted to the garage building at the upper inner edges of the doors one arm of each lever being pivoted to the upper edge of the door, as at 9. A cable 10 is connected to the other arm of the bell crank lever and extends therefrom over a guide pulley 11 secured to the rear wall of the garage and is attached to the eye 7^a at the rear end of the ramp plate, it being understood that this arrangement is duplicated with respect to each door and companion ramp plate and that the disposition of the bell crank levers is such (see Figs. 80 3 and 4) that the doors will be closed by a pull on the cables imparted thereto by downward movement of the rear ends of the ramp plates pivoted at the lower portion of the garage building at the sides of the door opening, one end of each lever being pivoted to the lower end of the door, as at 13, and the other end of the lever connected by cable 14 to the inner end of the ramp controlling the opening of said door, said cable 85 being guided by a pulley 15 secured in the rear end of the recess 6 in which the ramp plate operates. The intermediate portions of the cables 14 extend under the floor and the inner ends of the said cables are connected to 90 the eyes 7^a at the inner ends of the ramp plates 7.

In operation, and assuming the parts to be in the positions as shown in Figures 1 and 2 of the drawings the forward wheels of an 100

automobile, when it is run into the garage will ride on the ramp plates 7 and swing the said plates so that the rear ends thereof are moved from an upper position to a lowered position within the recess, and said plates will 5 pull the cables 10 to operate the bell crank levers 8 to close the doors. At the same time, the bell-crank levers 12 operate to take up the slack on the cables 14 and the forward ends of the ramp plates are swung upward so 10 that when the automobile is backed out of the garage the front wheels will depress said forward ends of the ramp plates to rock them and thereby operate the bell-crank levers 12 15 for automatically opening the doors. As the front wheels of the automobile leave the ramp plates, they travel upon the upper surface of the floor and the ramp plates 7 return to their normal position as shown in Figures 1 20 and 2 of the drawings or in position to close the doors when the automobile is again driven into the garage.

From the above description taken in conjunction with the accompanying drawings, 25 it will be seen that mechanism for automatically opening and closing the doors of a garage, of simple and durable form, is provided, and that the parts are operatively connected with the doors in such manner that 30 when the automobile machine enters the garage the doors are automatically closed behind the automobile machine, and when the automobile machine starts to leave the garage the doors are automatically opened.

35 Having thus described my invention, what I claim as new is:

In combination with a garage building having hinged doors and spaced apart recesses in the floor at a distance from the doors, 40 upwardly curved ramp plates pivoted intermediate their ends in said recesses to have a rocking movement therein, that part of the ramp plates immediately above the pivots being on a plane approximately with the floor 45 of the garage, and each of said plates having a rib at its underside terminating in an eye, bell-crank levers pivoted to the door frame at the upper and lower ends of the doors and connected thereto for opening and closing 50 the same, and cables connected to the eyes of the ramp plates and extending in opposite directions therefrom to the aforementioned bell-crank levers at the upper and lower ends of the doors respectively.
